UNITED STATES PATENT OFFICE.

ADOLPH OLEVIN, OF DETROIT, MICHIGAN.

LOOM-PLATE AND HANGER.

1,390,921.

Specification of Letters Patent. Patented Sept. 13, 1921.

Application filed January 28, 1920, Serial No. 354,645. Renewed August 3, 1921. Serial No. 489,570.

To all whom it may concern:

Be it known that I, ADOLPH OLEVIN, a citizen of the United States, residing at Detroit, in the county of Wayne and State 5 of Michigan, have invented certain new and useful Improvements in Loom-Plates and Hangers, of which the following is a specification.

My invention relates to loom plates and 10 means for suspending the same from an overhead track. The object is to provide a loom plate of the usual form, and means whereby the same may be suspended from a cleat hanger or overhead track of peculiar 15 construction so as to support considerable weight, the suspension means being so fashioned that the plate may be positioned on the cleat or track from which it is suspended by the adjustment of a screw; the 20 track and the supporting means depending therefrom being so constructed that when the adjustment screw is tightened the plate is perfectly centered and an exceedingly secure jointure is made between the hanger 25 and track.

The device is in form as follows—

Figure 1 is a vertical cross section.

Fig. 2 is a view looking upward at the plate, the fixture removed.

30 Fig. 3 is a horizontal section taken on the line 3—3 of Fig. 1.

In the drawings:

Let *a* represent the track or overhead cleat, which is in the form of a double *U* 35 with upraised intervening central portion *b*, provided with a *U* shaped side flange on each side, indicated as *c* and *d*. This track is in the form of a hanger cleat and here shown as provided with apertures *e*. 40 so that the same may be nailed or otherwise fastened in place. The form here shown illustrates a hanger to which my fitting is attached for use in connection with a ceiling light.

45 *f*, indicates a loom plate, *g*—*g* are punch outs for the passage of wires therethrough in number as may be desired. This loom plate is provided with openings near its central portion through which pass the parallel arms of a supporting member.

The supporting member or fitting proper 50 consists of a short tubular section *h*, externally threaded at its lower extremity to receive a light fixture threaded thereon as 55 shown at *i*, which may be of any desired form. This tubular section *h*, is carried

by two parallel supporting arms *j* and *k*, which extend outwardly and upwardly therefrom and project up through the loom plate through the passageways hereinbefore referred to, and are bent over at their extremities in the form of a hook to overhang the *U* shaped side flanges *c* and *d* of the track.

Internally at its upper extremity, the tubular section flares outwardly forming an oblong enlarged passageway, as at *l*, so that the substantially square nut *n*, will have its corners engaged by the narrowed opposed ends of this oblong enlarged opening. The outward flare of the passageway and the size of the nut *n*, will prevent the nut from falling through the passageway, and the oblong character of the flare will prevent rotation of the nut as the corners are engaged by the narrowed ends of the flared opening. This nut *n*, carries an adjusting screw *m*, threaded therethrough so as to be forced upwardly against the loom plate clamping the supporting members *k* and *j*, down firmly over the *U* shaped side flanges of the track and holding the device firmly in position.

It will be seen that in the positioning of the fixture, the loosening of the adjusting screw will permit the hanger to be moved longitudinally of the cleat or track *b*, so that the fixture may be positioned where desired.

It is further apparent that due to the peculiar construction of the track member, 90 a comparatively light construction will support a considerable weight, and that the tendency toward lateral displacement of the fixture where a flat bar is utilized as a cleat and the fixture is a heavy one, will be overcome, because the hanger will be rigidly positioned against such form of lateral distortion.

While it will be apparent that the illustrated embodiment of my invention herein disclosed is well calculated to adequately fulfil the objects primarily stated, it is to be understood that the invention is susceptible to variation, modification and change within the spirit and scope of the subjoined claims.

Having described my invention, I claim:

1. In a device of the class described, a supporting bar in the form of an inverted *U*, with upwardly extending side flanges 110 forming parallel troughs on either side, a loom plate, means for supporting a fixture

positioned below said loom plate, provided with two parallel upwardly extending arms projecting through said loom plate on opposite sides of said bar, said arms being 5 bent over at their extremities so as to overhang the side flanges of said troughs, means for tightening said loom plate against said bar.

2. In a device of the class described, a 10 supporting bar in the form of a double U with an intervening section at the upper extremity of its inner side walls, a loom plate, a tubular fitting provided with two opposed upwardly extending arms projecting 15 through said loom plate one on either side of said U bar, said arms bent over at their upper ends to hook over the side flanges of said bar, an adjusting screw carried internally of said tubular fitting adapted to 20 impinge said loom plate as the screw is tightened and exert downward pull on said upwardly extending arms which engage the supporting bar.

3. In a device of the class described, a 25 supporting bar in cross section in the form of a pair of U shaped parallel troughs spaced apart with an intervening web section, a loom plate, a tubular fitting adapted to support a fixture and provided with two 30 opposed upwardly extending arms projecting through said loom plate on either side of said supporting bar said arms bent over at their upper ends to engage the side flanges of said troughs, a screw carried in-

ternally of said tubular fitting adapted to 35 impinge said loom plate as the screw is tightened and provided with means to exert downward pull on said fitting so as to clamp the overhanging ends of said upwardly projecting arms firmly over the side flanges of 40 said troughs.

4. In a device of the class described, a supporting bar in cross section in the form of an inverted U with upwardly extending side flanges forming U shaped parallel 45 troughs one on either side of said inverted U a loom plate, a tubular fitting the interior of which flares in oblong form at its upper extremity, upwardly extending arms carried by said fitting bent over at their upper 50 extremities to engage the side flanges of said bar, a nut loosely carried in the flared oblong opening of said tubular fitting provided with an adjusting screw axially threaded therethrough said nut shaped so 55 as to be engaged by the narrowed ends of the oblong flared opening in said tubular fitting to prevent rotation thereof coincident with the rotation of the screw, said screw to be tightened so as to impinge the 60 loom plate and exert downward pull on the upwardly extending arms which overhang the supporting bar.

ADOLPH OLEVIN.
